UNITED STATES PATENT OFFICE.

ERNEST DE NEEN ANDERSON, OF NEW YORK, N. Y., ASSIGNOR TO UNION PAPER COMPANY, OF NEW YORK, N. Y.

MACHINE FOR MAKING PAPER BOXES.

1,089,619.

Specification of Letters Patent.

Patented Mar. 10, 1914.

Application filed July 9, 1909. Serial No. 506,688

To all whom it may concern:

Be it known that I, ERNEST DE NEEN ANDERSON, a citizen of the United States of America, residing at New York city, in the county of New York and State of New York, have invented certain new and useful Improvements in Machines for Making Paper Boxes, of which the following is a specification, reference being had therein to the accompanying drawing.

This invention relates to certain new and useful improvements in machines for making boxes or receptacles of various kinds. It is primarily intended for assembling together certain telescoping or interrelated parts of paste-board or other material that have previously been finished by other mechanism to serve in the construction of a box, receptacle, or holder of any kind. One particular kind of box with which it is especially adapted for use consists of a cylindrical or tubular body or element that is insertible into another cylindrical or tubular body, one form of which is a flanged disk to be tightly applied to one end of the other part to serve as a bottom or a cover. It should be understood, however, that the machine has a wide variety of applications and may be employed in the manufacture of boxes, receptacles, or packages having many different forms made of various materials and intended for manifold uses.

The object of the invention is to simplify and perfect the construction of an automatic machine of the class designated, in order that the parts of the boxes that are to be connected together may be rapidly applied to each other and a large number of the desired articles completed with ease in a short time without requiring a skilled operator for the machine, all the care required of the attendant being merely the feeding into the machine of the separate parts and the disposition of the resulting completed boxes, packages, or articles, as they leave the machine.

The invention consists essentially of automatic means for inserting a tubular element into another tubular element, or cylindrical body; or, more specifically, inserting a tubular or cylindrical body into a tubular or cylindrical cover or bottom, which latter may be open or closed at one end; also in means for sufficiently distending said tubular or cylindrical bottom or cover at the

moment of its application to the body to secure a tight fit; also in means for automatically applying an adhesive material to one of the component parts before they are attached to each other; and the invention furthermore may be said to comprise numerous details and peculiarities in the construction, arrangement and combination of parts substantially as will be hereinafter described and then more particularly pointed out in the appended claims.

In the accompanying drawing illustrating my invention, Figure 1 is a front elevation of my improved machine for assembling the parts of boxes, packages and the like, with certain parts thereof broken away. Fig. 2 is an end elevation of the same. Fig. 3 is an enlarged sectional side view on the line *a* *a* of Fig. 5. Fig. 4 is an enlarged detail view of the gluing device and its reservoir, the latter being indicated in section. Fig. 5 is a top plan view of the entire machine. Fig. 6 is an enlarged edge view of one of the feed belt pulleys and the mechanism for intermittently driving the same. Fig. 7 is a side view of the same mechanism shown in Fig. 6. Fig. 8 is an enlarged elevational view of the central portion of the machine, bringing out more clearly the relative position of many of the important mechanical parts which are delineated on a smaller scale in Figs. 1 and 2. Fig. 9 is a diagrammatic bottom plan view of a portion of the gluing head and the cooperating glue delivery wheel, to indicate more clearly the relative rotatory motion of these two parts and the method of transmitting the glue from the reservoir to the head. Fig. 10 is a top plan view of the trap device. Fig. 11 is a cross section of the same on the line *b* *b* of Fig. 10. Fig. 12 is an enlarged cross section of one of the feed belts, and a portion of the wheel on which it travels, and indicates one of the belt lugs or pins, and the means for holding the latter in place on the belt. Fig. 13 is a detail side view of the plunger, the means for operating the same, and certain other associated parts. Fig. 14 is a side elevation of the gluing head and shows its main relative position and arrangement. Fig. 15 is an enlarged detail sectional side elevation of the gluing head and means for supporting the same. Fig. 16 is a bottom plan view of the gluing head. Fig. 17 represents a side view

and an edge view of one of the fingers of the gluing head. Fig. 18 is a sectional side view of the plunger rod which operates the plunger, and the bearings in which said rod reciprocates. Fig. 19 is a cross section on the line *c-c* of Fig. 18. Fig. 20 is a detail view of the casting serving as a carrier in which the fingers of the gluing head are pivotally hung. Fig. 21 is a top plan view 10 of the distending or expanding mechanism for one of the telescoping parts of the box. Fig. 22 is an enlarged sectional view of the distending mechanism, the supporting trap for the box bottom, and shows the manner 15 in which the plunger introduces the body of the box down into the bottom and carries the finished product downwardly through the machine to be discharged therefrom.

Similar characters of reference designate 20 corresponding parts throughout all the different figures of the drawing.

Obviously the general frame-work of the machine in which the various mechanical elements are situated and relatively arranged for operation may vary within wide limits, and I do not wish to be restricted to any particular kind of frame. Many kinds of main frame may be employed. As an example of frame work, however, 1 designates the bed plate supported on suitable legs 2. The bed plate 1 is preferably of a longitudinal horizontal form. Horizontally opposite to and preferably at a suitable point above the bed plate 1, adjoining one 25 end of the latter, is a platform 4 on which are first placed a pile of box tubes or bodies upon which the machine is to operate, some of which are shown at 3, and similarly opposite the bed plate 1, near the other end 30 thereof, is another platform 6 on which the covers or bottom pieces 5 are placed. An attendant transfers the tubes, which in this case are the bodies 3 from the table 4 to an adjoining feed belt which conveys them in 35 the direction shown by the arrow in Fig. 5 toward the center of the machine; and an attendant also transfers the other tubes that are to be telescoped with the first-mentioned tubes which in this case are the bottoms or 40 covers 5 from the table 6 to another feed belt which carries them in the direction of the arrow shown in Fig. 5 toward the center of the machine. Thus it will be seen that there is a series of tubular bottoms or covers 45 moving in one direction, and a series of cylindrical bodies or tubes 3 moving in the opposite direction, with the object, of course, of having them meet in the central part of the machine where the automatic devices 50 are in operation for the purpose of taking each one of the tubes as it comes along and inserting it into one of the bottoms or covers, in the way that I shall proceed to explain in detail.

The cylinders or tubes 3 are conveyed by

an endless belt or carrier 7, and the bottoms or covers 5 by a similar endless belt or carrier 8. These belts or carriers are shown in side view in Fig. 1 and in plan view in Fig. 5. The belt 7 passes around two wheels 9, 9 whose shafts 10 are journaled in standards 11, there being a pair of these standards 11 for each shaft 10. Standards 11 are bolted securely upon the bed frame 1. Likewise the belt 8 passes around the two 70 wheels 12 which are similar to the wheels 9. Said wheels 12 are carried by shafts 13 that are journaled in standards 14, there being a pair of these standards for each shaft 13. Standards 14 are bolted upon the bed frame 80 1. Horizontal rails 15, 15 are bolted or otherwise firmly secured upon the upper ends of the pairs of standards 11, and similar horizontal rails 16, 16 are bolted or otherwise firmly secured upon the upper 85 ends of the standards 14. Thus there are two rails 15 stretching from one pair of standards 11 to the other pair of standards 11 with an intervening space between them, as indicated in Fig. 6, where the belt 7 90 travels, and this belt is supported and slides upon the parallel flanges 15^a formed by indentations in the opposite inner edges of the rails 15, so that the belt is allowed to be flush with the top surfaces of rails 15. See 95 Fig. 6. Similarly, the rails 16 stretch from one pair of standards 14 to the other pair of standards 14, and there is an intervening space between these rails in which the other belt 8 travels flush with the top surface of 100 the rails 16 and moves upon the flanges 16^a. See Fig. 14. The rails 15 and also the rails 16 are provided at one or both sides with vertical guide rails 17 and 18^a as shown in 105 Figs. 6 and 14, for the purpose of keeping the cylindrical bodies and the bottoms or covers in place while being fed forward. At convenient intervals apart, there being only enough space left between them to accommodate the individual cylinders or covers, these belts 7 and 8 are provided with 110 lugs or pins 18. The detailed construction of these pins is shown in Fig. 12. They are simply hollow metal projections which are clamped to the belts by means of screws 115 19 passing through the belt from the under side and having a convex head 20, while the threaded portion of the screw engages a correspondingly threaded passage within the pin 18. Thus the series of pins 18 is 120 clamped firmly to each belt. Consequently on the under side of each belt 7 and 8 there is a series of screw heads 20 and these enter concave recesses or perforations 21 in the periphery of each of the wheels 9 and 12, as 125 shown in Fig. 12. The concave recess 21 is deeper than the screw head 20, so that the latter does not entirely fill the recess, and so when it enters the recess it preferably only touches a portion of the wall 130

thereof, it being only necessary, in order to secure the best results, that these concave recesses in so receiving the screw heads should engage them with sufficient grip to 5 guide the belts properly forward. As each of the wheels 9 and 12 is furnished with a peripheral series of these concave recesses 21, it will, of course, be readily apparent that during the revolution of said wheels 10 the belts 7 and 8 will be steadily fed forward, the screw heads successively entering into and withdrawing from the recesses, and thereby giving a positive and steady action to the movement of the belts. Belt 8 travels 15 in a horizontal plane slightly below the plane of travel of belt 7, in order that the bottom or covers 5 may be delivered to the center of the machine at a point below the point of delivery of the cylinders or bodies 20 3. See Fig. 22. There is a space between the end of the belt 7 and the adjacent end of belt 8, wherein are located two horizontal plates 22 and 23, which are supported by means of vertical bolts 24, 24 rigidly secured to the bed frame 1. Belt 7 delivers the cylinders or bodies 3 individually upon the top of the plate 22, as shown in dotted lines at 3 in Fig. 22, and the forward movement of the series of cylinders 3 will finally 25 place each one at the center of the plate 22. Belt 8 feeding from the opposite direction delivers the covers or bottoms upon the lower plate 23, one of them being shown in dotted lines at 5 in Fig. 22, and each bottom 30 or cover is finally landed at the center of the plate 23 directly below a body or cylinder 3, and ready to receive said cylinder 3 when it is forced down thereinto and telescoped therewith by the movement of the 35 plunger.

The belts 7 and 8 are urged forward intermittently in opposite directions, as already stated, so as to carry the cylinders or tubes and the bottoms or covers to the 40 points where they are dropped, the same being the positions indicated in dotted lines in Fig. 22; while, as stated, the row of tubes and the row of covers or bottoms that follow thrust each one in succession under the 45 plunger. This intermittent forward movement of the belts is accomplished in the following way: 25 denotes a main driving shaft which is supported in bearings 26, 26 and carries a driving pulley 27. On this 50 main shaft 25 is a pinion 28 which meshes with a gear wheel 29 on a counter shaft 30. See Figs. 1 and 2. The counter shaft 30 is supported in bearings 31 formed as hangers and that are rigidly bolted to the bed frame 1. On the shaft 30 is a cam 32 operating 55 within a yoke 33 which is rigidly attached to a rock shaft 34 journalled in bearings 35 which are firmly bolted to the bed frame 1. Furthermore on the rock shaft 34 are rigidly 60 attached two forwardly projecting arms 36 and 37, one of which, as 36, is vertically below the innermost belt wheel 9; while the other arm, as 37, is vertically below the innermost belt wheel 12. On the outer end of each of the arms 36 and 37 is a sleeve 38 held loosely thereon between a shoulder 39 and a washer 40, the latter being kept in place by means of a pin 41. See Fig. 3. The sleeve 38 has lugs or ears 42 that are drawn together by means of a bolt 43. This 70 bolt serves as a pivot for the connection of a rod 44 to the sleeve 38, and hence a universal joint or a connection allowing movement in two directions is effected between the upwardly-extending rods 44 and the 75 arms 36 and 37 which are vibrated by the rocking of the shaft 34 under the impulse of the cam 32 working in the yoke 33. These two upwardly extending rods 44 pass through slots 45 in the bed frame 1, and are 80 connected by means of a pivot 46 to lugs 47 on a sleeve 48, having a pin 49 adjustably secured in a slot 50 formed in an arm 51 loosely supported on the shaft 10 of the belt wheel 9, or the shaft 13 of the belt wheel 12, 85 as the case may be. Each of these arms 51 carries a spring pawl 52 which engages successively the perforations or concave recesses 21 in the periphery of the wheels 9 and 12. As the upwardly extending rods 90 44 reciprocate in consequence of the rocking of the shaft 34, the arms 51 are intermittently lifted and the pawls 52 caused to feed the wheels 9 and 12 intermittently forward, 95 thus giving short positive impulses to the 100 two belts.

On the inner end of the counter-shaft 30 is a crank 53, to which is pivoted a connecting rod 54, the other end of which is pivoted to a sleeve 55 clamped firmly to the 105 lower end of a vertical plunger rod 56. Said clamping sleeve 55 is provided with a suitable pin that engages a perforation in the end of the connecting rod 54, as shown in Figs. 1 and 3. The plunger rod 56 preferably occupies a vertical position and reciprocates under the actuation of the crank 53 and connecting rod 54. It works in bearings 57 secured to the bed plate 1 above and below the same. See Fig. 8. A stout spring 110 58 is fastened at one end to the lower end of the plunger rod 56, or to the sleeve 55, and at the other end to the bed plate 1, and serves to counterbalance the movement of the plunger rod. Said rod 56 is provided 115 at a convenient distance above the bed plate 1 with a bracket or arm 59 that carries the plunger head or plunger 60, which is a mandrel or follower device. The latter is simply a solid piece of metal in cylindrical 120 form having a rounded bottom end 61. Above this lower end 61 and at some suitable points on the plunger 60 I provide a number of inclined faces or flat surfaces 60°, see Fig. 22, which serve to engage the upper 125

edge of the tube or cylinder 3. There is thus above the rounded end 61 a circumferential shoulder 61^a horizontally placed or at right angles to the axis of the plunger 60, and contiguous to this are the faces 60^a. The upper part of plunger 60 enters a clamping portion of the bracket 59 and is securely held therein, said bracket 59 having another clamping portion which fits over 10 and is securely bolted around the plunger rod 56. This arrangement is indicated quite clearly in Fig. 13. Thus the plunger 60 occupies a vertical position parallel to the plunger rod 56, and reciprocates in unison therewith. Plunger 60, as indicated in Fig. 15, enters each of the box bodies 3 in succession, and on its downward movement carries these bodies individually down into the bottoms or covers 5 waiting to receive them, 20 as I have already pointed out to some extent and as I shall more fully explain in speaking of the operation of the machine. Furthermore, the plunger rod 56 is provided at its upper end with another bracket arm 62 having an extension 63 which carries a spring buffer 64. See Figs. 8 and 13. This spring buffer 64 at each reciprocation of the plunger rod 56 and plunger 60 strikes against the upwardly-projecting spring- 30 provided rod 82 belonging to the gluing head, and actuates said head. Thus it will be seen that upon the rotation of the driving pulley 27, the plunger rod 56 is caused to vertically reciprocate, the result of which is 35 to impart an up-and-down motion to the plunger 60 and to the spring buffer 64, said plunger performing the assembling process of the box cylinder and the cover or bottom, and said spring buffer depressing the gluing 40 head and bringing about the result of applying the proper amount of glue or other adhesive material to the flange of the box end, that is to say, to one of the tubular parts, as will shortly be stated in detail. The 45 plunger rod 56 has therein a key-way 65 (see Fig. 18) which receives a rib or key 66 within one of the bearings 57, so that said plunger rod 56 while being vertically-reciprocatory will be non-rotative.

50 At the left hand end of the machine, the shaft 10 of the outer belt wheel 9, which shaft 10 occupies bearings in the standards 11 (see Fig. 6) is extended to form a horizontal shaft 67 on which are two pulleys 68 and 69. A belt 70 leads from the pulley 68 to a pulley 71 on the inclined shaft 72 of a glue-supplying wheel 74 operating to lift the glue or other adhesive from a reservoir 75 and apply it to the gluing head. See 55 Fig. 4. A belt 76 leads from the other pulley 69 around a pulley 77 placed horizontally upon a shaft 78. On the upper end of this shaft 78 is another pulley 79 from which a belt 80 leads to and around a pulley 81 on the shaft 82 of the gluing head, so

that a constant rotary motion may be applied to said head. Thus it will be seen that the main driving pulley 27, when it imparts motion to the main shaft 25, actuates also the shaft 67 and transmits motion to the 70 gluing head for the purpose of rotating the latter, and also to the glue wheel in the glue vat for the purpose of supplying an adhesive material to said head.

Referring to Figs. 21 and 22, I call attention again to the top center plate 22 which has a central opening through which the plunger 60 reciprocates. There is also the bottom plate 23, heretofore mentioned, which is a short distance below the plate 22, 75 and also has a similar but preferably larger opening. The opening in plate 22 is designated by the reference numeral 84 and has a circular form. In this opening is a radial series of pivoted fingers 85. The periphery 85 of the opening 84 is provided with radial slots 86, and crossing said slots is a circular groove 87. Each of the fingers 85 has oppositely-projecting lateral pins 88, and when the fingers are in position these pins 88 lie 90 in the circular groove 87, and the fingers themselves are seated in the radial slots 86 with their inner ends contiguous to each other around a central open space seen at 95 in Fig. 21. A circular coiled spring 90 lies beneath the series of radial fingers 85 and engages depending lips 91 on said fingers, said spring 90 serving to hold the fingers in the horizontal position indicated in full lines in Figs. 21 and 22, where their 100 upper edges are aligned substantially with the surface of the top plate 22 and where they jointly form a support on which the box body 3 may temporarily rest, as shown in full lines at the center in Fig. 21. But 105 these fingers are capable of being depressed under the action thereabove and thereupon of the plunger 60, and its lower rounded end 61, the effect of such depression being to 110 overcome the tension of the spring 90 temporarily, and thus cause the fingers to be deflected downwardly out of the position shown in full lines in Fig. 22 into the position shown in dotted lines in the same figure. The inner free ends of the fingers 85 115 are thin and narrow or pointed, being preferably reduced to a knife edge, so as to be of very inconsiderable thickness, in order that they may engage the cover or bottom 5 and occupy only a very small amount of 120 room therein. The effect of the downward deflection of these fingers and their introduction into the cover 3 simultaneously with the introduction of the plunger 60 and the body 3 into said cover will be to slightly 125 distend said cover, and compel it to receive the body 3 with a tight telescoping action. The lower center plate 23 having an opening somewhat larger than the opening 84 in plate 22, said opening in plate 23 being 130

designated by the reference numeral 92, carries a spring trap, as it may be called, which is shown in detail in Figs. 10 and 11. This trap consists essentially of four or more 5 spring leaves 93 of a general triangular shape, having their apexes contiguous to each other around a small central open space at 94. These leaves 93 are hung on shafts 95 which are journaled in the plate 23 and 10 are provided with springs 96 so tensioned as to normally keep the leaves 93 in the horizontal position shown in Fig. 22, but will permit of the leaves being depressed below said horizontal position when the box parts 15 and the plunger operate to pass them, said springs having the function of returning the leaves 93 to their normal horizontal position again after the operation of uniting the box parts is over. The manner in which the 20 leaves 93 are hung on their rods 95 in the plate 23 is illustrated fully in Figs. 10 and 11. Said leaves 93 are preferably provided with perforated ears 93a. In the case of two of the leaves 93, the supporting rods 95 25 pass entirely through the plate 23. In the case of the other two, for convenience of construction, it is found desirable to cut recesses at 97 in the plate 23 and insert therein perforated boxes 98 that hold the ends of 30 the shafts or rods 95, said boxes 98 being held in place themselves by means of screws 99 (see Fig. 11).

It has already been seen that in the operation of the machine there will be a simultaneous delivery of a bottom or cover 5 at 35 the center of plate 23, and a cylinder or tube 3 at the center of the plate 22 immediately above the bottom or cover 5. At such time therefore the tube 3 will rest upon the supporting fingers 85 and the cover 5 on the trap composed of the leaves 93. When the plunger 60 descends, the faces 60a just above the rounded lower end 61 of said plunger engage the tube or cylinder 3 and it is carried down also, and as the plunger strikes the fingers 85 the result is the opening of the fingers 85; and the tube 3 is carried down with the plunger which operates upon tube 3 so that the latter is introduced into the 40 cover or bottom 5 at the same time that the knife edge or thin ends of the fingers 85 enter the inside of the flange of cover 5. The effect of the introduction of these fingers into the cover or bottom 5 is to slightly 45 distend the same, and they accurately and surely guide the entry of the tube 3 into the bottom 5 and cause it to be seated firmly within the said bottom down against the disk or end portion of the latter. A very 50 tight fit of the two telescoping parts is thus secured. It is quite necessary that the diameters of the cover or bottom 5 and that of the tube 3 should closely approximate each other, so that a tight connection may be possible, and in order to avoid any irregularity 55

in the connection of the two parts, or any crushing or improper action of the same, it is necessary that fingers of this kind having an expansive or distending action should operate to spread the flange of the cover or bottom just enough to allow the tube to snugly pass thereinto. As the plunger continues in its downward course after the union of the two parts, the trap flies open, its leaves 93 overcoming the tension of the 60 upholding springs, and the finished product is discharged through it as the plunger finishes its descent, the completed box consisting of the combined parts 3 and 5, as shown in dotted lines in Fig. 22, being delivered from the machine upon a chute or discharge spout as 100 (see Fig. 5) by means of which the boxes are thrown out of the machine. As the plunger 60 rises again into its normal position to do the same work over again, 65 the trap will close and also the distending device, said trap assuming its horizontal position to receive the next cover or bottom 5, and said distending device likewise assuming its horizontal position to receive the next 70 tube or cylinder 3.

I will proceed now to describe the gluing or pasting mechanism by means of which the gluing head is supplied with the adhesive material required to firmly glue the cover 75 or bottom 5 to the tube or cylinder 3.

I have already mentioned the vat 75 containing adhesive material in which the wheel 74 revolves. This wheel is a disk having a beveled edge, which latter edge revolves at 80 times in contact with the gluing head. By referring to the diagrammatic view of Fig. 9, it will be seen that the wheel 74 revolves in one direction, and the gluing head in the same direction, so that when the two are in 85 contact the result is that the proper amount of glue is applied to the head to effect the necessary adhesive result, all surplus glue being scraped off by the contact of the two 90 rotary elements.

101 denotes a stationary standard which is securely bolted to the bed frame 1 at a point not very far from where the plunger rod 56 reciprocates through said bed frame 1. Securely fastened to the standard 101 is 105 a horizontal bracket 102, in the outer end of which is a bearing 106, through which the vertical rod 82 of the gluing mechanism moves up and down. On the upper end of this rod is a collar 103 held in place by a set 110 screw 104. A spring 105 is tensioned between the collar 103 and the aforesaid bearing 106 in the outer end of the bracket 102.

I have already stated that the plunger rod 56 not only carries the plunger 60, but also 115 a spring hammer 64 held by an arm 63 supported at the top of the rod 56. This spring hammer 64 at each reciprocation of the plunger rod 56 strikes the upper end of the main 120 rod 82 of the gluing mechanism and drives 125

the same downwardly, so that the glue supplying devices may act within the cover or bottom 5. (See Figs. 14 and 15).

In the lower portion of the gluing head 5 there is a sort of brush consisting of a circular series of fingers 83. One of these is shown in detail in Fig. 17. They are shaped so as to provide glue-receiving faces 107 at the lower end, and sprung-receiving-notches 108 at the upper end; while at a short distance below the spring-receiving notches 108 there are laterally-projecting pins 109 on each side, serving as pivots on which the fingers are hung.

Referring to Fig. 20, there is seen to be a circular casting 110 having therein a series of radial notches 111, the top surface of the casting being crossed by a circular groove 112 which provides a recess in the upper side of each of the segments between the radial notches or slots 111. The fingers are arranged within the radial slots 111 and the pins 109 are seated in the circular groove 112 acting therein as pivot pins on which the fingers can swing, so that their lower ends and their gluing surfaces 107 may be thrown in and out. The casting 110 is integral with the main rod 82, and below the casting 110 is a cylindrical downwardly extending part 113. The fingers 83 are arranged in a circular series around said part 113. Thus it will be seen that these fingers together constitute a sort of brush, since the lower ends thereof are arranged in a circular group, and at said lower end they are distensible, or extensible, so that they can be spread out to occupy a position of greater diameter at one time and drawn in close against the downward extension 113 so as to occupy a position of contracted diameter at another time. When expanded, the lower ends of these fingers are brought into contact with the inside of the encircling flange of the cover or bottom 5, as shown in dotted lines in Fig. 15; but when drawn in they are moved sufficiently far inwardly to clear them from any contact with the cover or bottom, and hence to occupy the position shown in full lines in Fig. 15. A circular spring 114, similar to the spring 90 belonging to the expanding fingers 83, surrounds this group of gluing fingers 83, and, as I have stated, enters the notches 108 in the upper end of each of them, the effect of said spring 114 being to draw the upper ends of the fingers together, and thus throw out their lower ends. This happens when a cone device 115, which works loosely on the main rod 82, above the slotted section 110, is lifted away from the upper ends of the fingers so as to release the latter. When the cone device 115 is pressed down tightly within the space occupied by the upper ends of the fingers 83 and against them above the cast-

ing 110, and above their pivotal points, the effect is to throw the lower ends of the fingers into their innermost or idle position, as shown in full lines in Fig. 15. The cone 115 is formed integral with or is securely fastened to a circular horizontal disk 116 through which the main rod 82 of the gluing mechanism passes. Above the disk 116 a short distance is another disk 117, preferably of less diameter than disk 116, and firmly secured to the rod 82 in like manner as is the pulley 81 close by which it is located. A series of vertical spiral springs 118 are interposed between the two disks 116 and 117. Thus the disk 116 and cone 115 are susceptible of more or less vertical movement at times, being transferable from the position shown in full lines to that shown in dotted lines in Fig. 15, and the resiliency of the springs 118 has the function after the compression of said springs of returning the disk 116 and cone 115 to the position shown in full lines. A series of pins 119 carried by the cone 115 and disk 116 project loosely into receiving recesses in disk 117 and serve to cause these parts all to rotate together, while at the same time the movement of the disk 116 relatively to the disk 117 is not prevented.

On the standard 101 at a suitable point below the top bracket 102 there is attached an arm or yoke 125 which projects around or partly around the series of fingers 83, as shown in Fig. 14. This yoke or arm 125 is in a position vertically below the disk 116 in its vertical reciprocations, and on each downward plunge of the gluing head the disk 116 strokes against the horizontal stationary arm 125, with the result that said disk is thereby stopped and can not move farther; while the downward impetus of the gluing head causes the springs 118 to be compressed for a short time, that is to say, while the series of fingers 83 move on downwardly for a short distance, although the movement of the disk 116 has been stayed by this contact with the arm 125. The halting of the disk 116 simultaneously stops the cone 115, and the continued movement a short distance of the series of gluing fingers 83, after the stopping of the cone 115, allows the upper ends of the fingers to be set free from contact with the cone 115, so that the spring 114 will act to draw in the upper ends and thrust out the lower ends of said fingers; and, as at this time, the gluing head will be inserted within the flange of the cover or bottom 5, as shown in dotted lines Fig. 15, the gluing faces 107 will be brought in contact with the inside surface of this flange, and will wipe the same and deposit adhesive material thereon in the proper quantity. On the next ascent of the gluing head, as soon as the disk 116 is released from

contact with the arm 125, the springs 118 will extend and the cone 115 will again assume its position in contact with the upper ends of the fingers 83, throwing the same 5 outwardly, and consequently throwing the lower ends of fingers 83 inwardly where they will be grouped together in the group of smallest diameter. When the fingers are thus grouped together closely, the glue- 10 transferring wheel 74 will act thereon and apply glue from the vat.

At the lower end of the gluing head below the extension 113 of the part 110 is a spring 120 which is inserted into the bottom 15 or cover 5 (see Fig. 14) just prior to the entrance of the gluing head into the latter, and serves to exert a pressure upon the bottom or cover and to hold it in position while the glue is being applied, and also to hold 20 it during the withdrawal of the gluing head, and to prevent it from moving upward when the gluing head ascends, serving as a sort of ejecting device for preventing the cover or bottom from being lifted by reason of 25 the adhesive material which might otherwise cause it to be carried upward with the gluing head. From what I have just said, therefore, it will be understood that when the gluing head is in its uppermost position, 30 the group of gluing fingers will be contracted into a small diameter; but when they are caused to descend into the flanged cover or bottom, they will be expanded into a position of greater diameter to perform the 35 gluing function. When grouped together into a small compass in the lifted position, they come into contact with the gluing wheel, as shown in Fig. 4; but when depressed, they are free from said wheel. 40 Hence, between every two actions of the fingers upon the box parts, said fingers are supplied with a fresh deposit of glue.

In order to keep the row of cylindrical bodies 3 in proper feeding position on the 45 belt 7, and also the row of bottoms or covers 5 in proper feeding position on the other belt 8, I employ pins 18 on said belts as indicated in Fig. 12. A row of bodies 3 is also shown in Fig. 5, as well as a row of bottoms 50 5. In the latter figure, it is observed that the bodies 3 and bottoms 5, respectively, lie between the pins 18. It is necessary, however, under ordinary circumstances to provide some ponderable device which can rest 55 on the tops of the parts 3 and 5 and keep them from jumping out of position vertically during the rapid operation of the machine. Hence I secure alongside of each of the moving belts 7 and 8 a standard 127. 60 See Figs. 1 and 8. Each standard carries a pivoted arm 126, which, being of iron or some heavy material, may lie upon the parts 3 and 5, and, being pivoted, may be so easily movable that the feeding of the parts

3 and 5 will be in no wise obstructed, while 65 at the same time they will be kept from jumping vertically out of their normal position between the pins 18.

The invention is broad enough to cover not only the particular box described, but 70 all kinds of boxes, receptacles, cartons and the like, and it embraces within its scope not alone the telescoping of a tubular part within another tubular part, but the insertion 75 of a part having any desired shape within another part having a corresponding shape. In using the terms "body", "bottom", "cover", "tubular body", "cylindrical body", "flanged disk", etc., I am not to be restricted to the particular form shown 80 and described, as these are simply offered by way of example. The special kind of box which is shown with its parts in process of assembling throughout the drawing is only one of a great variety of receptacles 85 whose parts may be put together by my improved machinery. Therefore it is to be understood that my invention permits a wide variation from the special construction shown and described, and that a great many 90 changes may be made in the mechanism without going outside of the invention as defined in the claims, and I reserve the liberty of making all such changes as may be found necessary in practice, as the invention 95 is equally serviceable in the case of the assembling of two tubes by telescoping one within the other, or the assembling of other parts of different shapes by inserting one 100 within the other in the manufacture of boxes and cartons either of pasteboard or any other material, whatever may be the size, character of the intended contents, style of the package, etc.

Having thus described my invention, what 105 I claim as new and desire to secure by Letters Patent, is:

1. In a box-making machine, the combination with means for feeding a tubular part of the box, of means for feeding a cover 110 for one end of said tube, so that the two may be placed in juxtaposition, means consisting of a plunger for introducing one part within the other, expanding means whereby one part is slightly distended at the moment of 115 the introduction of the other thereinto, and ejecting means for the finished product.

2. In a box-making machine, the combination with means for feeding a tubular part of the box, of means for feeding a 120 cover for one end of said tube, so that the two may be placed in juxtaposition, means for introducing one part within the other, and expanding means whereby one part is slightly distended at the moment of the 125 introduction of the other, said expanding means comprising a series of pivoted radial fingers.

3. In a box-making machine, the combination with means for presenting a tubular part of the box and a cover for one end of the same simultaneously, of means consisting of a plunger for introducing one part within the other, and expanding means whereby one part is slightly distended at the moment of the introduction of the other thereinto.
- 16 4. In a machine for making boxes, the combination with means for causing two parts of the box to telescope with each other, of means for slightly distending one part at the moment of the introduction of the other thereinto, said distending means consisting of a series of pivoted radial fingers.
5. In a machine for uniting the parts of boxes and the like, the combination with means for introducing one part within another part of corresponding shape, of means for slightly distending the receiving part at the moment of the introduction of the other thereinto, said distending means consisting of a series of pivoted radial fingers.
6. In a machine for making boxes and the like, the combination with means for bringing two parts into a position in alignment with each other, means for introducing and securing one part within the other, and means for expanding the receiving parts simultaneously with the introduction of the other thereinto, said latter means consisting of a series of withdrawable pivoted radial fingers.
7. In a machine for making boxes and the like, the combination with means for feeding one part into the machine, means for feeding another part into a position where it will be in alignment with the first part, means for causing one part to enter into the other, means for distending the receiving part simultaneously with the introduction of the other thereinto, said latter means consisting of a circular series of attenuated fingers and a spring device arranged in connection therewith.
8. In a box-making machine, the combination with intermittently-operating means for simultaneously presenting a tubular portion of the box and a cover for one end of the same, of means for causing one of the parts to telescope within the other, means for supplying an adhesive, and means for distending one of the parts at the moment of the introduction of the other thereinto.
9. In a box-making machine, the combination with intermittently-acting means for simultaneously bringing a tubular part of the box and a cover for one end of the same into telescoping juxtaposition, of means for effecting the telescoping, means for distending one of the parts at the moment of telescoping, means for supplying an adhesive, and means for ejecting the finished product.
10. In a box-making machine, the combination with intermittently-acting means for simultaneously presenting a tubular part of the box and a cover for one end of the same so that the two parts may temporarily be in juxtaposition to permit telescoping, means for effecting the telescoping of the two parts, and means for distending one of the parts so as to allow the other to be tightly introduced thereinto, said distending means consisting of a series of radial fingers hung pivotally and acting within the inside surface of one of the parts and withdrawable after the telescoping is finished.
11. In a box-making machine, the combination of means for presenting a tubular part of the box and simultaneously presenting a cover for one end of the same, distending mechanism consisting of a series of fingers on which the tube normally rests, and trap means consisting of yielding elements on which the cover normally rests directly opposite the tube, and means consisting essentially of a plunger for moving the tube past the distending mechanism and overcoming the resiliency of the trap, said distending mechanism acting simultaneously with the plunger to expand the cover at the moment of the introduction of the tube thereinto.
12. In a machine for making boxes, the combination of means for feeding one part to the machine, means for feeding another part, so that the second part will be aligned with the first, and means for causing one part to be introduced into the other, consisting essentially of a plunger having lateral flat surfaces thereon.
13. In a machine for making boxes, the combination of means for alining the parts of the box which are to be united, and means for causing one part to be introduced into the other, said latter means including a plunger having a rounded end and a series of lateral flat surfaces contiguous to the rounded end.
14. In a box-making machine, the combination with means for feeding a part of the box, of means for supplying an adhesive to the interior thereof, consisting essentially of a circular series of pivoted fingers and a spring-actuated cone device operating in conjunction with said fingers so that the latter may be contracted into a brush of small diameter at one time and expanded into a brush of larger diameter at another time, and means consisting of a rotary adhesive-supplying wheel, into contact with which the brush comes when it is contracted in diameter.
15. In a box-making machine, the combination with means for feeding a tubular part, of means for feeding a second tubular

part so that it will occupy a position in alinement with the first, means for supplying an adhesive to one part consisting essentially of a brush composed of a series of 5 expandible and contractile fingers, which fingers receive adhesive and expand within one of the tubes to apply it thereto, means for causing one of the tubes to be telescoped within the other, and means for distending 10 the receiving tube at the moment of the introduction of the other thereinto.

16. In a box-making machine, the combination of means for feeding a tubular part, means for feeding another tubular part, the 15 two feeding means operating toward each other and delivering at points one above the other so that the two parts thus delivered may be in alinement with each other, yielding means receiving the tubular parts from the feeding means and supporting them temporarily, said means consisting of a plurality of spring-provided devices, means for introducing one tubular part within the other consisting essentially of a plunger and mechanism for driving it, said plunger in 20 its operation overcoming the tension of the aforesaid yielding devices.

17. In a box-making machine, the combi-

nation with a feeding belt for delivering a tubular part, a second feeding belt for delivering another tubular part, yielding means for receiving one part, said means consisting of a circular series of spring provided fingers, yielding means for receiving the other tubular part, said means consisting of a plurality of spring-provided leaves, the two parts of the box being in alinement with each other when so delivered, and means for introducing one part within the other consisting essentially of a plunger, said plunger 30 in its operation overcoming the tension of the yielding devices in both cases, the yielding fingers in the one case operating simultaneously with the action of the plunger to distend the receiving tube. 35

18. In a box-making machine, the combination of the plunger, distending fingers for expanding one of the box parts, and an ejecting trap for removing the finished article. 40

In testimony whereof, I affix my signature in presence of two witnesses.
